UNITED STATES PATENT OFFICE.

ALBERT EDMONDSON, OF WARE, MASSACHUSETTS.

CLEANSING COMPOUND.

No Drawing.

Application filed December 4, 1924. Serial No. 753,965.

To all whom it may concern:

Be it known that I, ALBERT EDMONDSON, a citizen of the United States of America, residing at Ware, in the county of Hampshire and State of Massachusetts, have invented certain new and useful Improvements in Cleansing Compounds, of which the following is a specification.

The present invention relates to a new and useful cleansing compound.

The primary object of this invention is to provide a cleansing compound which may be used for cleaning raw fibres, fabrics, clothing, or any other articles or objects desired, either by the manufacturers during the stages of producing the same or by the consumers after they have purchased the finished products.

A further object of the invention is to provide a cleansing compound which may be used independently for cleaning such articles or objects as mentioned above or in combination with other cleansing compounds, such as soaps, powders, or fluids, which have more of a suds or lather producing nature.

A still further object of the invention is to provide a compound formed of ingredients which may be combined with the ingredients now being used in the manufacture of commercial soaps and cleaning powders and fluids for producing better cleaners.

Other objects and advantages of the invention will be apparent during the course of the following description.

This invention contemplates the provision of a cleansing compound to be formed by the combining of sodium carbonate (soda ash) and hydrous sodium sulphate (Glauber's salts) which may be used independently of or in combination with other cleansing compounds, such as soaps, powders, or fluids, for cleaning raw fibres, such as wool or cotton; dyed or undyed fabrics either prior to or after being made into wearing apparel; and any other articles or objects desired, either by the manufacturers during the several stages of production or by con-

sumers after they have purchased the finished products. These ingredients may be compounded in any desired proportions, but I have found, by a series of experiments, that a compound consisting of three parts or seventy-five per cent of sodium carbonate and one part or twenty-five per cent of hydrous sodium sulphate will produce the desired result in a very efficient manner.

It may be found, in using this compound for washing objects or articles, that the washing bath or fluid will lack the desired amount of suds or lather, and, for this reason, the combining of this compound with soaps or washing powders or fluids may be desirable. It is also suggested that the above mentioned ingredients may be compounded with the ingredients now being used in the manufacture of commercial soaps and washing powders or fluids for producing better cleaning products. The combining of these ingredients with washing compounds renders the latter less irritable.

It will be noticed in using this compound of sodium carbonate and hydrous sodium sulphate in a scouring machine for cleansing wool that the latter will leave the machine in a permanently better condition, the fibers being more open and fluffy, the color more pronounced, and the wool will have a nice, soft, velvety feel.

I am aware of the fact that sodium carbonate has been used for cleansing fibers and fabrics, but when used without hydrous sodium sulphate, the fibers or fabrics are given a hard feel; and if they are normally white, the sodium carbonate will give them a yellowish tinge. The adding of the hydrous sodium sulphate overcomes all of these bad effects.

Having thus described my invention, I claim:

A cleansing compound consisting of 75% of sodium carbonate and 25% of hydrous sodium sulphate.

In testimony whereof I affix my signature.

ALBERT EDMONDSON.
